CLAIM

The ornamental design for an angular strut bracket, as shown and described.

DESCRIPTION

FIG. 1 is a top-front-left perspective view of an angular strut bracket showing my new design;

FIG. 2 is a bottom-rear-right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
